UNITED STATES PATENT OFFICE.

GEORGE PHILLIPS, OF TILFORD, ILLINOIS.

SCREEN-FRAME.

SPECIFICATION forming part of Letters Patent No. 298,116, dated May 6, 1884.

Application filed January 3, 1884. (No model.)

To all whom it may concern:

Be it known that I, GEORGE PHILLIPS, of Tilford, in the county of Jefferson and State of Illinois, have invented a new and Improved 5 Frame for Door and Window Screens, of which the following is a full, clear, and exact description.

The object of my invention is to provide a new and improved screen-frame for doors and 10 windows, which frame can readily be adjusted in height and width.

The invention consists in the construction and arrangement of parts, as will be herein-after fully described, and specifically set forth 15 in the claims.

Reference is to be had to the accompanying drawings, forming part of this specification, in which similar letters of reference indicate corresponding parts in all the figures.

20 Figure 1 is a face view of my improved adjustable frame for door and window screens, parts of the netting being broken out. Fig. 2 is a longitudinal side edge elevation of the same. Fig. 3 is a sectional plan view of the 25 same on the line $\alpha\alpha$, Fig. 1.

The screen is formed of the top and bottom bars, A and B, and the side bars, C. The top and bottom bars are each formed of two sections, A' A² and B' B², respectively, and the 30 side bars, C, are each formed of two sections, C' C². The section A' of the top bar is provided in the under edge with a recess extending from the inner end to within a short distance of the outer end, and the section A² is provided on the top edge with a recess extending from the inner end to within a short distance of the outer end. The bottom bar and the side bars are all constructed in the same manner, and for this reason the top bar, A, will 35 only be described in full. The sections A' A² are each provided in each side surface with a longitudinal groove, a , and on the end of each section A' A² a clip, D, is fastened on each surface, the clips projecting beyond the inner longitudinal edges of the said sections, and the 40 ends of the clips being bent inward to form hooks d . The hooks d of the plates or clips D on the section A' pass into the opposite grooves, a , in the section A², and the hooks

50 of the clips or plates D on the section A² pass into the grooves a in the section A'. The sections forming the bars are thus held together in such a manner that they can slide on each other in the direction of the length of the bars, thus permitting of lengthening or shortening the bars, as may be necessary. A binding-screw, E, of any suitable construction, is held at the end of the section A² of the bar, and in the end of the corresponding section of each other bar, the said screw projecting from 60 the inner surface of the bar. The said screw serves for locking the bar-sections in the desired position. The outer edge of each side bar is provided with a longitudinal groove, F, for receiving the strip on the window-casing, 65 for the purpose of holding the screen-frame in place in the casing. On the ends of each side bar two clips or plates, G, are held, which project over the ends of the said bars, and have hooks g formed on the projecting ends, which hooks 70 pass into grooves h on the side surfaces of the top and bottom bars, A, B, at the outer ends. The side bars, C, are thus held removably on the ends of the top and bottom bars, but can be held securely on the ends of the said top 75 and bottom bars by means of screws m , passed through screw-holes n in the projecting ends of the clips or plates G. If the screen is very high, the side bars, C, can be united by a cross-bar, J, constructed in the same manner as the 80 other bars, and secured to the inner edges of the side bars by means of angle-irons K. The screen-frame can thus be adjusted to fit a door or window opening of any size within the limits of the frame, and after the frame has 85 been adjusted the netting is secured on the same. When the frame is not in use, it can be folded very compactly, so as to occupy a very small space.

Having thus fully described my invention, I 90 claim as new and desire to secure by Letters Patent—

1. A screen-frame having its bars formed of two sections having longitudinal recesses in the adjoining edges, and each section having 95 longitudinal grooves in the side surfaces, and two clips or hook plates, one being fastened to the inner end of each section, the hooks on

the plates of one section passing into the longitudinal grooves in the other section, substantially as herein shown and described.

2. In a screen-frame, the combination, with 5 the end bars having longitudinal grooves in the side surfaces, of side bars, and of hook-plates or clips secured on the ends of the side bars, the hooks of the said hoop-plates or clips passing into the grooves in the end bars, substantially as herein shown and described.

3. In a screen-frame, the combination, with end bars having longitudinal grooves in the

surfaces, of side bars, and of hook-plates or clips secured on the ends of side bars, the hooks of the said plates or clips passing into 15 the grooves in the end bars, and the said hooks or plates being provided in the projecting ends with holes, through which screws can be passed, substantially as herein shown and described.

GEORGE PHILLIPS.
